FIG. 8.

INVENTOR
P. MACGREGOR

BY *Frank J. Scholten*

ATT'Y.

UNITED STATES PATENT OFFICE.

PETER MACGREGOR, OF OTTAWA, ONTARIO, CANADA.

FASTENING DEVICE FOR BINDING-BARS AND SIMILAR PURPOSES.

No. 872,948.

Specification of Letters Patent.

Patented Dec. 3, 1907.

Application filed April 6, 1907. Serial No. 366,836.

To all whom it may concern:

Be it known that I, PETER MACGREGOR, of the city of Ottawa, in the county of Carleton, Province of Ontario, Canada, have invented 5 certain new and useful Improvements in Fastening Devices for Binding-Bars and Similar Purposes, of which the following is a specification.

My invention relates to improvements in 10 fastening devices for binding bars and similar purposes and its object is to provide an efficient form of fastening device, which may be directly stamped in the binding bar and which will operate to effectually secure the 15 binding cord thereto; and it consists essentially of the improvement hereinafter fully described in the accompanying specifications and drawings and specifically set forth in the claims.

20 In the drawings, Figure 1 is a perspective view of a binder having the binding bar formed with fastening devices in accordance with my invention. Fig. 2 is a perspective view of the bound matter when withdrawn 25 from the binder and tied ready for permanent filing. Fig. 3 is a perspective view of the binding bar. Fig. 4 is a perspective view of an alternative form of the lower binding bar, which may be conveniently used in combination with my upper bar. Fig. 5 is a sectional view taken longitudinally through the binding bars. Fig. 6 is a sectional view along the line 2—2, Fig. 5. Fig. 7 is an enlarged sectional detail of the connections between 35 the binding cover and the binding bar. Fig. 8 is a longitudinal section of the upper binding bar.

In the drawings, like letters of reference indicate corresponding parts in each figure.

40 A and B are any suitable form of binding covers connected by a flexible connecting piece C of binding cloth or the like. D and E are the binding bars of suitable stiff material, such as sheet steel, which are hinged to the inner edge of the binding covers, preferably by a hinge of binding cloth, which also extends to cover the bar itself as shown.

Each of the binding bars are provided with two open slots a and b, which, as shown, in 50 Fig. 3, are substantially L-shaped and in accordance with my invention, two fastening devices c and d are stamped in the binding bar in alignment with the inner portions of the open slot.

5 As shown, these fastening devices are each formed by two tongues m and n stamped in

the top of the binding bar and being first curved upwardly to extend above the binding-bar and then downwardly to extend below the surface. By this means a cord wound 60 around the fastening device is depressed by the tongues into the slot beneath the tongues, the co-action between the tongue and the edges of the slot operating to efficiently lock the cord.

65 In the alternative form of binding bar shown in Fig. 4, similar fastening devices o and p are provided in the bottom to those in the top, and a cord is wound around these and through two open slots q and r provided 70 in the edge of the bar. The material f to be bound is provided with perforations f and g through which the cord is led. The cord is also wound through the open slots in the binding bars and then tightened by securing 75 to the fastening devices. This will bind the material firmly in position as shown in Fig. 6.

When it is desired to remove the bound material as a whole the cord is unwound 80 from the fastening button and slipped out of the slots in the binding bars. The ends may then be tied together, as shown in Fig. 2, holding the bound material together and ready for permanent filing.

85 From the foregoing description, it will be evident that I have provided a fastening device for binding purposes, which renders the binder capable of operating with a greater degree of efficiency while at the same time, it decreases its cost of production.

90 While, the particular application of the fastening device described herein, is to binding bars, yet it will be evident that it can be applied to any similar purposes in which it is desired to removably attach a cord to a 95 plate or bar.

What I claim as my invention is:—

1. In a temporary binder, a binding bar having a fastening device stamped in the top thereof integral therewith, the said fastening device including a resilient member integral with the bar and extending downwardly into a slot cut therein, as and for the purpose specified.

105 2. In a temporary binder, a binding bar having a fastening device stamped in the top thereof integral therewith, the said fastening device including a plurality of divergent resilient members integral with the bar and extending below the surface thereof, as 110 and for the purpose specified.

3. An improved fastening device for secur-

2
ing a cord to a plate or bar, comprising a plate, a resilient tongue cut therein having a portion downwardly curved and extending below the surface of the plate as and for 5 the purpose specified.

4. An improved fastening device for binding bars and the like comprising a plate, a resilient tongue therein having an inner portion upwardly curved above the surface of 10 the plate and the outer portion downwardly curved to extend below the surface of the plate, as and for the purpose specified.

5. In a temporary binder, a binding bar having an inclined slot cut in the edge thereof, and a fastening device stamped in the top therof, the said fastening device being in 15 alinement with the inclined slot and including

a resilient member integral with the bar and extending downwardly into a slot therein.

6. In a temporary binder, a binding bar 20 having an inclined slot cut in the edge thereof, and a fastening device stamped in the top thereof, the said fastening device being in alinement with the inclined slot and including a resilient member integral with the bar 25 and extending downwardly towards said slot and adapted to press the cord downwardly into the slot.

Signed at Ottawa, in the Province of Ontario, this 30th day of March, 1907.

PETER MACGREGOR.
